UNITED STATES PATENT OFFICE.

GEORGE WARREN WILSON, OF BOSTON, MASSACHUSETTS.

INCANDESCENT ELECTRIC LAMP.

SPECIFICATION forming part of Letters Patent No. 414,741, dated November 12, 1889.

Application filed January 24, 1889. Serial No. 297,356. (No model.)

To all whom it may concern:

Be it known that I, GEORGE WARREN WILSON, of Boston, in the county of Suffolk and State of Massachusetts, have invented a new 5 and useful Improvement in Incandescent Electric Lamps; and I do hereby declare that the following is a full, clear, and exact description of the same.

My invention is an improvement in incandescent lamps in which the filament is held within an air-tight globe and is in the form of a loop; and its object is to provide a reflecting-surface between the limbs of the filament, which shall break up and distribute 10 the light in the most effective manner, and at the same time to prevent short-circuiting or bombardment between the filament-limbs, which is so destructive to the material of the filament.

20 My present invention consists of a hollow reflector located between the limbs of the filament and composed of transparent non-conducting material, such as glass, whereby the rays of light are not only reflected from the convex surface of the reflector, but are also reflected and distributed from the interior concave surface of the said reflector.

I do not claim, broadly, herein a reflector interposed between the limbs of the filament, 30 limiting my claims in this application to a transparent tubular reflector.

In another application, dated March 7, 1889, Serial No. 302,240, I have claimed, broadly, the placing of a reflector between the limbs of the 35 filament, and consequently disclaim this broad subject-matter in this case.

In the accompanying drawings, Figure 1 represents a side elevation of the lamp partly broken away, and Fig. 2 a detail view of a 40 modification.

In the drawings, A represents the globe of the lamp; B, platinum terminals of the wires which form, with the filament C, the arc of the lamp.

45 D is any suitable filling in the neck of the globe by which it is closed and the parts are held in place. In this filling is set rigidly a reflector or distributor E for the light, which extends between the limbs of the filament, 50 and forms a reflecting-surface for the limbs upon both sides of the reflector. This re-

flector must be of non-conducting material, in order that it may not impair the working of the lamp. Its surface must be adapted to reflect the light, and for this purpose any 55 suitable or well-known material may be used, but it is either itself wholly non-conducting or is insulated upon some non-conducting part of the reflector. The reflector is made preferably of glass; but mica may be 60 used, or other transparent materials which the skill of the workman would readily suggest. In shape it is made preferably round in cross-section, and, as shown in the figures, conforms approximately to the shape of the 65 globe—that is to say, it is made narrow or contracted as it approaches the neck of the globe. An excellent effect is produced by a plain glass reflector made hollow or tubular, and interposed in the manner described between the limbs of the filament. The glass 70 in this case has smooth interior and exterior surfaces, all of which serve to break up and disperse the light and prevent the light-waves from neutralizing each other to a very 75 great extent. The reflector itself also serves as a support for the platinum terminals, if desired.

In the form shown in Fig. 2, which is a longitudinal section, a convenient mode of 80 uniting the reflector and the globe of the lamp is illustrated. In this the reflector is contracted, as above explained, and then expanded in this construction to form a neck b, which fits snugly within the neck of the 85 globe, and may be fused, cemented, or otherwise secured thereto. At the enlargement of the neck of the reflector, at points indicated by a, perforations are made through which the platinum terminals pass, and thereby the 90 neck of the reflector is made to serve as a support for these terminals and the filament thereon. Not only does the reflector thus break up and disperse and thus utilize all the rays or waves of light, but it also prevents 95 what is called "bombardment" and short-circuiting, and greatly increases the usefulness of this class of lamps.

I claim as my invention—

1. In combination with an incandescent 100 electric lamp, a non-conducting transparent reflector in tubular form interposed between

the limbs of the filament, substantially as described.

2. In combination with an incandescent electric lamp, a non-conducting transparent reflector interposed between the limbs of the filament and having diverging sides, substantially as described.

In testimony whereof I have signed my name to this specification in the presence of two subscribing witnesses.

GEORGE WARREN WILSON.
